UNITED STATES PATENT OFFICE.

JOHN PARKINSON, THOMAS M. MARTIN, AND CALVIN C. BOWEN, OF LOS ANGELES, CALIFORNIA, ASSIGNORS TO THE PACIFIC ELEVATOR COMPANY, OF SAME PLACE.

ELECTRIC ELEVATOR.

SPECIFICATION forming part of Letters Patent No. 556,435, dated March 17, 1896.

Application filed February 7, 1895. Serial No. 537,658. (No model.)

To all whom it may concern:

Be it known that we, JOHN PARKINSON, THOMAS M. MARTIN, and CALVIN C. BOWEN, of Los Angeles, county of Los Angeles, in the 5 State of California, have invented certain new and useful Improvements in Electric Elevators, of which the following is a full, clear, and exact description, reference being had to the accompanying drawings, which form a 10 part of this specification.

Our invention relates to certain improvements in elevators, such as shown, described, and claimed in the application of John Parkinson, filed October 24, 1894, Serial No. 15 526,868, and our invention consists in certain features of novelty hereinafter described, and pointed out in the claims.

Figure I represents a transverse section taken on line I I, Fig. III, showing the motor 20 and manner of imparting motion to the driving-shafts. Fig. II is a bottom view. Fig. III represents a section taken on line III III, Fig. I. Fig. IV represents a front elevation of the operating lever and brake. Fig. V is 25 an edge view of the operating-lever. Fig. VI is a plan view of the hinged catch for holding the hand-operating mechanism out of gear.

Referring to the drawings, 1 represents the 30 vertical standards, preferably formed of channel-irons, between which the traveling elevator-frame 2 operates, said standards having vertical flanges 2 $\frac{1}{2}$.

3 represents paired racks on the outer faces 35 of the standards, there being preferably a series of four racks. 4 represents a corresponding number of paired pinions, which mesh with said racks, and which are rigidly secured to the ends of two drive-shafts 5, said drive-shafts being journaled at 6 to the traveling frame 2. The teeth 7 on the vertical racks and the gear 8 on the pinions 4 are preferably 40 of the stepped pattern, thus insuring a steady movement of the frame up or down, besides 45 other advantages derived from the use of this form of gear.

The pinions 4 are provided with flanges 9 at the outer ends of the gear, said flanges extending a short distance beyond the face of 50 the gear and to each side of the racks 3, thus

forming a guide for the pinions, the flanges on the pinions rotating against the flanges 2 $\frac{1}{2}$ on the standards.

10 represents worm or cog wheels secured rigidly to the center of the drive-shafts 5. 55

11 represents the motor suspended at or near the center of the traveling frame 2 by means of suitable brackets 12.

13 represents the motor-shaft, which extends nearly the length of the traveling frame 60 3 and at right angles with the drive-shafts 5.

14 represents worm-gears on the motor-shaft on each side of the motor, said worm-gears meshing with the cog-wheels 10 on the drive-shafts, thus imparting motion to the 65 drive-shafts in opposite directions, and through the medium of the pinions 4 and the vertical racks causing the frame or elevator to move either up or down, as directed.

15 represents a two-part casing inclosing 70 and protecting the cog-wheels 10 and worm-gears 14, said casing serving also to retain oil for lubricating said gears and cog-wheels.

16 represents a beveled gear-wheel secured rigidly near one end of the motor-shaft 13. 75 17 represents a vertical shaft journaled in a bracket 18, which is secured to the frame 2 at 19, said shaft being adapted to be moved up or down in its bearing. 20 represents a beveled pinion secured to the lower end of the 80 shaft 17. When the shaft 17 is lowered in its bearing the beveled pinion will mesh with the beveled gear 16 on the motor-shaft.

The upper end of the shaft 17 is provided with a squared end 21, on which a crank- 85 wrench 22 may be placed, said wrench being inserted through an opening 23 in the floor 24 of the elevator, the purpose of said wrench and shaft being to form a means of propelling the elevator by hand a short distance 90 should occasion ever require the same—such, for instance, as the electric current being shut off when the elevator is between floors.

The shaft 17 is limited in its downward movement by means of a collar 25 thereon, 95 the shaft and pinion being normally held out of gear by means of a hinged catch 25 $\frac{1}{2}$ being placed in close contact with the shaft and the collar resting on the same.

26 represents the operating-lever pivoted 100

- at 27 to a bracket 28, said bracket being secured to the traveling frame at 29.
- 30 represents a grooved pulley secured rigidly to one end of the motor-shaft.
- 5 31 represents a flexible strap or band having one of its ends secured at 32 to the bracket 28, the strap passing nearly around the pulley and resting in the groove of the same and having its opposite end adjustably secured 10 at 33 to the free end of a bar 34, said strap being made adjustable as to length by means of a nut 35 secured on its upper end. The opposite end of the bar 34 is pivoted to the traveling frame at 36.
- 15 37 represents a grooved roller journaled on a stud 38 on the operating-lever 26, said roller being located immediately beneath the bar 34.
- 39 represents a boss on the under side of the bar 34 in a vertical plane with the lever 20 26 when it is in its upright position.
- As the lever is brought to a vertical position by the operator the roller 37 will roll against the boss 39, raising the bar 34, thus lifting up on the flexible strap 31, thus forming 25 a frictional brake on the pulley 30 and stopping the elevator, it being understood that when the operating-lever is moved to a vertical position the electric current is shut off.
- 40 represents a broken connection leading 30 to the rheostat.
- 41 represents a lever pivoted to the operating-lever at 42, said lever 41 having an eccentric 43 on its lower end, said eccentric when the lever 41 is forced to one side coming 35 in contact with the edge of a quadrant 44, thus enabling the operator to hold the operating-lever at any desired position without causing any undue strain upon the hand and arm.
- 40 45 represents cross-bars which have their ends fitted in the channel-irons of the standards, thus serving to brace the standards.
- By the use of our channel-iron construction of the standards we form a combined rack and 45 standard that permits us to dispense with wooden standards, thus avoiding danger from fire as well as other advantages not necessary to mention.
- We claim as our invention—
- 50 1. The combination of the four standards each having on their outer sides a pair of racks formed with stepped teeth and flanges on both sides of the paired racks, the traveling frame, the driven shafts journaled to the traveling frame, the paired pinions formed with stepped teeth and with flanges bearing against the flanges of the standards, the worm-wheels secured to the driven shafts, the motor, and the motor-shaft having worm-gears and arranged transversely of the driven shaft; 60 substantially as described. 55
2. The combination of the four channel-standards, each having on their outer sides a pair of racks formed with stepped teeth and flanges on both sides of the paired racks, the cross-bars located between and fitted in the channel-standards, the traveling frame, the driven shafts journaled to the traveling frame, the paired pinions formed with stepped teeth and with flanges bearing against the flanges of the channel-standards the worm-wheels secured to the driven shafts, the motor, and the motor-shaft having worm-gears and arranged transversely of the driven shafts; 70 substantially as described. 75
3. The combination with the traveling frame, of the motor, the motor-shaft the bevel gear-wheel secured to the motor-shaft, the bracket secured to the traveling frame, the vertical movable shaft having a supporting-collar at 80 its upper end, and a bevel-pinion at its lower end, and the hinged catch; substantially as described.
4. In an elevator the combination, of a movable frame, a motor-shaft, a grooved pulley on the motor-shaft, an operating-lever pivoted to the movable frame, a roller journaled to the operating-lever, a movable bar having one of its ends pivoted to the movable frame, a boss on said bar, a flexible strap 90 having one of its ends fixed to the movable frame and its opposite end secured to the free end of the movable bar, said strap being adapted to engage the grooved pulley whereby the action of the roller on the movable bar 95 will contract the strap and thus form a brake on the motor-shaft; substantially as set forth. 85
